UNITED STATES PATENT OFFICE.

ARTHUR J. ADAMS, OF CHICAGO, ILLINOIS, ASSIGNOR TO FULTON MANUFACTURING COMPANY, OF CHICAGO, ILLINOIS, A CORPORATION OF ILLINOIS.

GO-CART OR BABY-CARRIAGE.

No. 925,741.

Specification of Letters Patent.

Patented June 22, 1909.

Original application filed May 7, 1908, Serial No. 431,312. Divided and this application filed January 6, 1909.
Serial No. 471,024.

To all whom it may concern:

Be it known that I, ARTHUR J. ADAMS, a citizen of the United States, residing at Chicago, in the county of Cook and State of Illinois, have invented a new and useful Improvement in Go-Carts or Baby-Carriages, of which the following is a specification.

My invention relates particularly to folding go-carts or baby carriages which are 10 adapted to be folded into compact space.

The present invention constitutes an improvement on the go-cart shown in my Patent No. 789,810, granted May 9, 1905.

My primary object is to provide improved 15 spring connections whereby the seat will be yieldingly supported in a go-cart structure.

The invention is illustrated in its preferred embodiment in the accompanying drawings, in which—

20 Figure 1 represents a side elevational view (slightly broken) of a cart constructed in accordance with my invention; Fig. 2, a broken view of one of the folding handle-bracing and seat - supporting bars employed, the 25 view showing the brace-bar partially flexed; Fig. 3, a similar view showing the members of the brace-bar locked in an extended position, this view showing the spring-barrel or housing in section; Fig. 4, a similar view 30 illustrating the limited flexing or yielding action which is permitted in the normal use of the go-cart; and Fig. 5, a broken plan view of the construction shown in Figs. 3 and 4.

35 In the construction illustrated, A represents the running-gear frame; B, pairs of wheels journaled on brackets B¹ connected with the running-gear frame by pivots B² and adapted to fold beneath the running- 40 gear frame in a well understood manner; C, a handle connected by hinges c with the rear portion of the running-gear frame; D, foldable brace-bars connecting the upper portion 45 of the handle with the front portion of the running-gear frame and forming with the running-gear frame and the handle a triangular structure, said brace-bars serving also as a means from which the seat may be suspended; E, a seat having its front portion 50 suspended by links E¹ from the bars D and having connected with its lateral edges side-flaps E² which are permanently secured to the bars D; F, a back having its lower portion flexibly joined to the rear portion of the

seat, said back being equipped at its lateral 55 edges near its upper end with eyes or loops F¹ adapted to be connected either with hooks carried by the brace-bars D or with hooks carried by the bars of the handle C, according to desire; and G, an automatically-locking, 60 self-releasing foot-rest adjustably connected with the lower portions of the bars D, in accordance with the construction described and claimed in my application No. 471,025, filed of even date herewith. 65

A pair of wheels B at each side of the cart is adapted to fold beneath the running-gear frame in a well understood manner, and the brackets B¹ are connected crosswise, in the extended position, by mechanism B³, which 70 forms no part of the present invention. The handle C comprises the usual side-members c¹ (one shown) whose lower ends are connected with the hinges c and whose upper ends are connected by a handle-round c². 75 Each side-bar c¹ of the handle is equipped with a back-supporting hook c³.

Each handle-bracing and seat-supporting device D comprises an upper link, or bar, d connected by a pivot d¹ with the upper portion of the corresponding side-bar of the handle; a lower bar, or link, d² connected at its front end, by a pivot d³, with the front portion of the adjacent side-member of the running-gear frame, and connected near its rear 80 end, by a pivot d⁴, with the front end of the bar d; and having an extension d⁵ in the rear of said pivot, as shown in Figs. 2 and 5; a relatively short bar d⁶ connected at its front end with the pivot d⁴ and having an offset 90 locking member or extremity d⁷ at its rear end, and equipped adjacent to the member d⁷ with a spring-barrel d⁸, in which is confined a coiled spring d⁹ upon which the extension d⁵ of the link d² bears, as shown in Figs. 95 5 and 6; and a locking device d¹⁰ carried by the link d and adapted to engage the member d⁷ of the short link d⁶. The extension d⁵ of the link d² is confined between the short link d⁶ and the front portion of the link d when the 100 cart is in the open or extended position. Said extension d⁵ is equipped with a stud d¹¹ which extends through a slot d¹² in the short link d⁶, said stud being provided on the opposite side of the link d⁶ with a head d¹³. The 105 barrel or spring-housing d⁸ is provided at its front side with a slot d¹⁴ in which the extension d⁵ may work when the carriage is under

load. The locking device d^{10} comprises a clip d^{15} secured, by rivets d^{16} , to the bar d , and a slide d^{17} having flanges d^{18} between which the member d^7 is confined when the bars D are in the extended position. The member d^7 is provided with a bevel-edge d^{19} adapted to engage and retract the slide d^{17} , against the force of a spring d^{20} which is confined between the clip d^{15} and the bar d .

10 From the description given it will be understood that when the seat is occupied the seat-supporting and handle-bracing devices D will be slightly flexed, the springs d^9 yielding under the load. It is observed that the locking member d^7 is offset or struck toward the bar d , as shown in Fig. 5.

15 The bars d are equipped with hooks d^{21} which comprise sheet-metal stampings whose shanks are secured to the bars d by the rivets d^{16} , the shanks of said hooks having their upper ends turned laterally to form flanges d^{22} which engage the upper edges of the bars d . When the back F is adjusted to accommodate the child in a sitting posture, the eyes F^1 20 or loops F^1 of the back engage the hooks d^{21} ; and when the back is adjusted to a reclining position, the eyes F^1 of the back engage the hooks c^3 , as described in detail in my pending application No. 431,312, filed May 7, 1908, 25 whereof the present application is a division.

The manner of use of the improved baby carriage or go-cart will be readily understood. When it is desired to allow the child to assume a sitting posture, the back F may be adjusted to the standing position shown in Fig. 1. When it is desired to allow the child to recline, the back may be disengaged from the hooks d^{21} and brought into engagement with the hooks c^3 on the handle-bars. 30 When it is desired to fold the cart, assuming it to be in the condition shown in Fig. 1, the locking members d^{17} may be moved rearwardly to release the locking members d^7 , whereupon the handle may be folded forwardly to a position substantially parallel with the running-gear frame, the braces D folding upon themselves in this operation, and finally assuming a position substantially within the plane of the running-gear frame 35 and between the side members a thereof; in a well known manner.

It will be observed that while the foldable braces D are rigid enough to perform their function of supporting the seat and bracing the handle, nevertheless, the springs d^9 will yield, under load, to prevent injurious jar to the child, in passing over rough places.

The foregoing detailed description has been given for clearness of understanding only, and no undue limitation is to be understood therefrom.

What I regard as new, and desire to secure by Letters Patent, is—

1. In a folding go-cart, the combination 65 with a running-gear frame, and a handle

foldably connected therewith, of a foldable seat-supporting and handle-bracing device connecting the handle and running-gear frame, and comprising yieldingly connected links permitting flexing, within limits, under load during normal use.

2. In a folding go-cart, the combination with a running-gear frame, and a handle foldably connected therewith, of foldable seat-supporting and handle-bracing devices connecting the handle and running-gear frame, each comprising pivotally connected front and rear brace-links, and spring connection at the junction of said brace-links permitting limited flexing of said links with relation to each other, under load.

3. In a folding go-cart, the combination with a running-gear frame, and a handle foldably connected therewith, of foldable seat-supporting and handle-bracing devices connecting the handle and running-gear frame, each comprising a front link pivotally joined to the front portion of the running-gear frame, a rear link pivotally connected with the upper portion of the handle, said links overlapping at adjacent ends; a pivot connecting said links in front of the rear end of the front link, a short link equipped with a spring adapted to support the rear end of the front link, and locking means connecting 95 said short link with said rear link.

4. In a folding go-cart, the combination with a running-gear frame and a handle pivotally connected with the rear portion thereof and adapted to fold forwardly upon the running-gear frame, of a foldable seat-supporting and handle-bracing device connecting the upper portion of the handle with the front portion of the running-gear frame, comprising a front link pivotally joined to the front portion of the running-gear frame, a rear link pivotally connected with the upper portion of the handle, a pivot connecting said links, the front link having a projection extending in the rear of said pivot, a pivotally attached short link at the joint between said first-named and second-named links, a spring barrel carried by said short link, a spring contained therein serving as a yielding bearing for said rearward projection of said first-named link, and locking means adapted to secure said short link to said second-named link.

5. In a structure of the character set forth, a foldable seat-supporting and handle-bracing device comprising a rear link, a front link, a pivot connecting said links some distance in front of the rear end of the front link, thus affording a rearward extension of the front link, a short link connected with said pivot and between which and the front portion of said rear link said extension is confined, said short link having an offset locking-member at its rear end, a spring-held locking member carried by said rear link, and a spring sup-

ported by said short link and serving as a support for the rearward extension of the front link.

6. In a folding go-cart, the combination with a running-gear frame and a handle foldably connected therewith, of foldable seat-supporting and handle-bracing devices connecting the handle and running-gear frame, each comprising pivotally connected front and rear links joined respectively to the running-gear frame and handle, yielding connections between the front and rear links permitting flexing, within limits, under load, and a seat suspended from said front links.
- 15 7. In a folding go-cart, the combination with a running-gear frame and a handle foldably connected therewith, of foldable seat-

supporting and handle-bracing devices connecting the handle and running-gear frame, each comprising pivotally connected front 20 and rear links joined respectively to the running-gear frame and handle, yielding connections between the front and rear links permitting flexing, within limits, under load, a seat suspended from said front links, a back 25 flexibly connected with the rear portion of said seat, and connections for said back carried by said rear links and by said handle, whereby the back may occupy either a standing or inclined position.

ARTHUR J. ADAMS.
